(57) **CLAIM**

The ornamental design for a scoop-spatula, as shown and described.

DESCRIPTION

FIG. 1 is perspective view of the scoop-spatula from a first angle;

FIG. 2 is a front elevation view of the scoop-spatula shown in FIG. 1;

FIG. 3 is a rear elevation view of the scoop-spatula shown in FIG. 1;

FIG. 4 is a right-side elevation view of the scoop-spatula shown in FIG. 1;

FIG. 5 is a left-side elevation view of the scoop-spatula shown in FIG. 1;

FIG. 6 is a top plan view of the scoop-spatula shown in FIG. 1;

FIG. 7 is a bottom plan view of the scoop-spatula shown in FIG. 1; and,

FIG. 8 is perspective view of the scoop-spatula shown in FIG. 1 from a second angle.

The broken lines throughout the drawings are utilized to show contoured surfaces of the scoop-spatula.

1 Claim, 6 Drawing Sheets
